(57) **ABSTRACT**

A system and method for synchronizing indicators of electronic gaming machines. The system providing a plurality of electronic gaming machines each having a control array and at least one electronic display operatively connected thereto, at least one lighting device operatively connected to the plurality of gaming machines and control circuitry, including a programmable processor, operatively connected to the lighting device. The lighting device having elements to present synchronized lighting effects at the plurality of gaming machines, the synchronized lighting effects including an attract mode and an emotive mode. The system registering a condition on at least one gaming machine and electrically transmitting a signal to the lighting device. The lighting device initiating a predetermined lighting effect at the plurality of machines in response to the registered condition.

**CROSS REFERENCE TO RELATED
APPLICATION**

The present application is a continuation of U.S. patent application Ser. No. 14/252,350 filed Apr. 14, 2014, now allowed, which claims the benefit of both U.S. Provisional Patent Application Ser. No. 61/812,104 filed Apr. 15, 2013 and U.S. Provisional Patent Application Ser. No. 61/838,112 filed Jun. 21, 2013. These applications are hereby incorporated by reference in their entirety as if set forth fully herein.

FIELD

The subject invention pertains generally to a system and method of synchronizing lights or other indicators in a plurality of gaming machines, and more particularly a system and method providing coordinated lighting effects based upon detected activity at an individual machine.

BACKGROUND

Electronic gaming machines (“EGMs”) are generally well known and have been relatively popular, and profitable, for a number of years. Examples of such machines include for example, video slot machines, video poker machines, bar-top gaming devices, and coin-operated amusement devices. Typically, EGMs are arranged at gaming venues in banks consisting of at least two EGMs that are physically located adjacent or proximate to one another. Usually, EGMs in a bank will be the same style or type, and/or be made by the same manufacturer. EGMs in a bank can also be networked or otherwise operably or electronically linked for communications purposes.

Some types of EGMs, and/or banks of EGMs, are known to have indicators, lights or luminescent devices, independent of their video monitors or electronic game displays, which can flash, blink, and flow in predetermined patterns. Such lights can be incorporated directly as part of the EGM, can be part of a unit that can be affixed to an EGM, or can be on a separate unit in close proximity to one or more of the EGMs. For example, certain types of EGMs can have an electroluminescent “topper” which can be physically mounted to an EGM, such as for instance, to the top portion of the EGM above the display or body of the machine so that they can be easily seen at a distance across a gaming venue. A bank of EGMs can also feature “bank signs” having one or more light fixtures. Such bank signs can be placed, for instance, above a bank of two or more EGMs in order to promote play of all the machines in the bank. Such bank signs can be mechanically or electrically coupled to one or more EGMs or be independently powered.

It is generally known in the art to synchronize lights in a bank of EGMs so that they illuminate in patterns suggesting that they are “flowing” from one EGM to another, or so that they illuminate in synchronization or in sequence. These light sequences, whether on individual EGMs, or in banks, can also be used for distinctive “attract mode” patterns which attempt to draw the eye of potential players. Such known synchronization techniques, however, do not take into account the status or activity of individual EGMs within the bank and further do not coordinate lighting effects among a plurality of EGMs based upon activity at individual

EGMs within a bank. Thus, such limitations are generally not as effective in drawing players to vacant or inactive gaming machines and can further cause players at individual machines to become distracted or annoyed with intense or lurid lighting effects at adjacent machines. As a result, players may have a more difficult time finding a vacant machine or may be more inclined to stop playing a machine due to distraction or overstimulation. This can lead to certain gaming machines being inactive for extended periods of time. As such machines are typically income producing, extended periods of inactivity can result in a loss of revenue for the gaming establishment. Thus, game developers and owners/operators are continually in need of new techniques for attracting interested players and maintaining player satisfaction.

In view of the foregoing, it would be useful, and thus there is a need, for a system and method that can coordinate lighting effects among a plurality of EGMs in response to detected conditions or activity at an individual EGM within a bank. It would be further desirable for such systems and methods to have multiple lighting modes which can be initiated depending on a detected condition or activity at an individual EGM. It will be recognized by persons of ordinary skill in the art that such techniques can be more effective in drawing players to inactive machines and can further maintain player satisfaction by not providing distraction or irritation.

BRIEF DESCRIPTION OF THE DRAWINGS

FIG. 1A is a block diagram illustrating a first representational view of a system in accordance herewith.

FIG. 1B is a block diagram illustrating a second representational view of a system in accordance herewith.

FIG. 2 is a block diagram illustrating an electronic gaming machine in accordance herewith.

FIG. 3 is a flowchart illustrating a method according to embodiments described herein.

DETAILED DESCRIPTION

While this invention is susceptible of embodiment in many different forms, there are shown in the drawings, and will be described herein in detail, specific embodiments thereof with the understanding that the present disclosure is to be considered as an exemplification of the principles of the invention and is not intended to limit the invention to the specific embodiments illustrated.

As described herein, embodiments of the subject invention are directed to a system and method for synchronizing or coordinating lights or other indicators in a plurality of gaming machines. Such embodiments provide for EGMs in a bank to be alerted as to whether one of the EGMs in the bank is actively being played by a player. Where none of the EGMs in the bank are in use, the lights associated with the EGMs can begin a “synchronized attract mode.” In this mode, the lights in the bank can gradually (or all at once after a predetermined lapse of time following the last “pull” on any machine in the bank, or when no machine has a current credit balance, or both) begin an aggressive lighting pattern where the lights flash brighter or with more intensity, at a more rapid pace or sequence and/or in more elaborate or complex patterns intended to draw attention to the entire bank of EGMs as well as to each EGM, individually.

Embodiments disclosed herein can also provide for alerting an individual EGM in a bank as to the initiation of play (or other activity) at an alternate EGM in the bank in order

to modify the synchronized attract mode. For example, when a player engages one of the EGMs in the bank, the lights associated with the other EGMs can remain in attract mode, but switch to a less aggressive “emotive” style of lighting characterized by less bright or slower lighting effects that are intended to avoid distraction or irritation to a player that is actively playing one of the EGMs. This practice could include either the lights of the entire bank of EGMs switching to emotive mode, or only switching selected lights which are the closest in proximity to the currently active EGM. Although known techniques can provide an emotive style of lighting for lights associated with a single EGM that is in use, embodiments disclosed herein provide for a novel system that can coordinate lighting effects across a plurality of EGMs in response to activity at one of the EGMs. Thus, such systems provide for changing lighting effects at a nearby EGM that is not in use, in response to use at another machine.

It will be recognized by persons of ordinary skill in the art that such functions can draw interested players to available or inactive machines and can further keep players at a machine for a longer period of time, thus increasing the potential revenue to the owner/operator of the gaming device. It will be further recognized that embodiments disclosed herein can provide for a more entertaining and enjoyable gaming experience to players by controlling lighting effects of a game.

According to embodiments presented herein, any kind of known lighting device or other kind of sensory output device can be coordinated or synchronized to create the desired lighting effect or mode. Such lighting devices can include, for example, light emitting diodes (“LEDs”), incandescent lamps, cold cathodes, lasers, fluorescent, halogen or neon lamps or tubes or any other type of illumination device. In addition, embodiments presented herein can further coordinate lighting effects produced by electronic display devices, such as for example LCD, LED, plasma or CRT monitors or backlit lighting devices having static images that are illuminated from behind by one or more light sources.

The lighting devices can be part of, or affixed directly to, the individual EGMs or plurality of the EGMs, or can be separate units that are physically detached from the EGMs in a proximate or nearby area. For example, embodiments disclosed herein can coordinate the lighting effects of electroluminescent “toppers” which can be physically mounted to an EGM, such as for instance, to the top portion of the EGM above the display or body of the machine so that they can be easily seen at a distance across a gaming venue. The coordination of lighting effects as described herein can additionally be carried out in connection with “bank signs” having one or more light fixtures. Such bank signs can be placed, for instance, above a bank of two or more EGMs in order to promote play of all the machines on the bank. Such bank signs can be mechanically or electrically coupled to one or more EGMs or be independently powered.

The lighting devices can be electrically coupled to an EGM in order to draw power directly from the machine through a power/control interface. According to such configurations, the lights can also be controlled through the EGM’s main programming interface, or through a program executed by an alternate electrical device, such as for example a common server, operatively connected to the EGM or lighting device.

With reference now to the figures, FIGS. 1A and 1B illustrate representational views of a system 10 according to embodiments of the subject invention. The system 10 can comprise a plurality of EGMs 12a . . . 12n and one or more

lighting devices 14a . . . 14n operatively connected to the EGMs 12a . . . 12n. As illustrated in FIG. 1A, each EGM 12a . . . 12n can include, and/or be individually connected to, a separate lighting device 14a . . . 14n, such as for example lights affixed directly to the machine’s housing or an electroluminescent topper mounted to the top of the machine. Additionally, or alternatively, the plurality of EGMs 12a . . . 12n can, as shown in FIG. 2B, be operatively connected to a common lighting device 14z, such as for example a bank sign or electronic display. The lighting devices 14a . . . 14n, 14z can incorporate any kind of lighting element as previously identified and described, or can contain multiple different kinds of lighting elements.

The EGMs 12a . . . 12n can be physically arranged in a single bank or in close proximity to one another and can have identical or related features, themes or games, or can be entirely different or otherwise unrelated. The EGMs 12a . . . 12n, 12z can be operatively connected to one another via wired or wireless connection 16 and can be further electronically connected to a common server 18 physically located in or around the bank of EGMs 12a . . . 12n, or elsewhere in a remote location.

The server 18 can receive electronic signals from the EGMs 12a . . . 12n as to game activities or conditions being performed thereon and can contain a programmable processor, circuitry and control programs stored on a computer readable medium for identifying and recording such conditions or activities. Such control programs and circuitry can contain stored data that can associate predetermined conditions or activities being carried out on an EGM 12a . . . 12n with predetermined lighting effects or modes. Thus, where a certain condition is detected, the server can transmit signals to the lighting devices 14a . . . 14n, 14z to control or adjust the lighting elements in the predetermined manner.

For example, where the lighting devices 14a . . . 14n, 14z are in a synchronized “attract mode” and a player starts playing a game on one of the gaming machines (e.g. 12a), the EGM 12a can send a signal to the common processor 18 that EGM 12a is active. The server 18 can in turn send a signal to lighting devices 14a . . . 14n, 14z, to adjust, modify or terminate the attract mode lighting effects. In adjusting such lighting effects, the lighting devices 14a . . . 14n, 14z (or portions thereof) can be directed by the server 18 to commence a less intense, emotive lighting mode, where, for example, the lighting elements flash with less intensity or frequency. In performing such synchronization, the lighting device 14a associated with the active EGM 12a can be adjusted in the same manner as the remaining lighting devices 14b . . . 14n, 14z, or can be adjusted in a different manner, such as for example, being turned off completely or being adjusted to present an “active” mode. In addition, where the system 10 incorporates a common lighting device 14a, as illustrated in FIG. 1B, different portions, sections or lighting elements of the device 14a can be adjusted depending on their proximity to an active EGM 12a. Thus, in synchronizing the lighting devices 14a . . . 14n, 14z in such a manner, the system 10 can control lighting effects so as not to distract or irritate the player that is actively playing one of the EGMs 12a.

Although the embodiments illustrated in FIGS. 1A and 1B are shown to include a common server 18, persons of ordinary skill in the art will recognize that a server 18 is not required and that system 10 can synchronize and coordinate the lighting effects with control programs and circuitry provided by the individual EGMs 12a . . . 12n or on some other kind of electronic device, such as for example, a computer, electronic tablet, smartphone or PDA operatively

connected to, or in electronic communication with, the system 10. Where the lighting devices 14a . . . 14n, 14z are controlled by the individual EGMS 12a . . . 12n, the EGMS 12a . . . 12n can control the synchronization of the lighting effects by transmitting signals directly to the lighting devices 14a . . . 14n, 14z or the other EGMS 12a . . . 12n as need be.

FIG. 2 illustrates an EGM 12 according to embodiments of the subject invention. The EGM 10 can include a programmable processor 20 (such as for example a microprocessor or microcontroller) operatively coupled to one or more game displays 22a, 22b. The processor 20 can include control programs 24 and associated circuitry and be operatively connected to a user interface 26 with input/output circuits and at least one storage unit 28 which can store a plurality of instructions executable by the processor 20. The processor 20 can also include memory 30 which can include a main memory containing dynamic information processed by the processor 20 during operation, and/or a static memory which contains fixed information, such as, for example, an operating system, game programs, and a configuration of information necessary for the processor 20 to register and execute input from a player through a control array 32.

The displays 22a, 22b can include any kind of electronic display device suitable for visually presenting dynamic video images or representations of a game played on the EGM 12. The displays 22a, 22b can be CRT, LCD, plasma or LED display devices or monitors and can be part of the EGM 12 by being enclosed in the same housing or cabinet 40 as the processor 20, or can be a separate unit either affixed to EGM 12 or physically detached from the EGM 12. The displays 22a, 22b can additionally include touch screen capabilities for receiving input from a player.

The processor 20 can execute the control programs 24 to perform primary functions for play the game, such as for example, randomly selecting game outcomes from a plurality of possible outcomes, recognizing a particular outcome as a predetermined winning or non-winning outcome and/or determining a reward amount associated with a particular winning outcome. The processor 20 can additionally control the game displays 22a, 22b by generating static or dynamic video for presentation thereon. The processor 20 and control programs 24 can additionally include applications for recording and/or registering game activity, or inactivity, which can be used to control the lighting devices 14a . . . 14n, 14z. Such activity or inactivity can be detected from the start or completion of a game program played on the EGM 12, by the deposit of wagers into an EGM 12, by physically detecting the presence of an individual in close proximity to the EGM 12, or by any other event or condition.

The control array 32 can include one or more input devices, such as for example, a keyboard, mechanical lever, a touch-screen, push buttons or pads and/or any other means for control, or desired combination of controls, able to accept input from a player and produce output to the game display 22a, 22b in response to a player's input. The EGM 12 or control array 32 can additionally include one or more sensors 34 for detecting motion or the presence of an individual at or around the EGM 12. Such sensors can include, for example photoelectric sensors, temperature sensors, infrared sensors, ultrasonic sensors, microwave sensors and/or any other type of device used for optical or acoustical detection. The sensors can be operatively coupled to the processor 20 which can register detection and associate such detection with predetermined lighting effects. Such predetermined lighting effects can be electronically stored as programmed data on a computer readable medium or can be generated through artificial intelligence ("AI") systems

incorporated by the EGM 12 or system 10 which can register activities and results against a ranking of possible results and generate lighting effects which have been identified as being associated increased or continuous play of the machines.

5 Where embodiments of the subject invention are practiced or provided in connection with a wagering game, the gaming machine 12 can further include a credit input device 36, such as for example a coin or bill acceptor or card reader and a payoff device 38. The credit input device and payoff device 10 can be operatively connected to the processor 20 and when money or other credits are deposited in connection with a game, the control program 24 can instruct the payoff device to issue an award in response to the selection of certain predetermined winning outcomes of the game. The reward 15 or payoff can be provided in any form, including for example, coins, bills, credits, points, cards, tickets or coupons.

The EGM 12 can feature or be operatively connected to one or more lighting devices 14, which, as previously 20 described, can be affixed to or otherwise be in close proximity to the EGM 12, such as for example, lamps, lights or other luminescent devices mounted to the top or side of the exterior housing or cabinet 40 of the EGM 12. Such lighting devices 14 can include LEDs, incandescent lamps, cold 25 cathodes, lasers, fluorescent, halogen or neon lamps or tubes or any other type of illumination elements.

The storage unit 20 or memory 22 can contain stored data 30 or analytics providing for certain lighting conditions or effects, such as for example certain attract modes or emotive style lighting modes as previously described. Thus, where a predetermined activity or period of inactivity is detected, the processor 20 can transmit instructions for controlling the lighting devices 14 to implement the corresponding lighting effect.

35 The gaming machine 12 can additionally feature communication means for electrically transmitting signals, including control signals, game data or detected conditions to a remote electronic device such as the common server 18 or lighting devices 14a . . . 14n, 14z as illustrated in FIG. 1A 40 or 1B, or any external device, such as for example, a computer, network or display device, dedicated storage device, or other mobile electronic device such as a PDA, smart phone, notebook computer or electronic tablet. Such communication means can include a communication interface 42 that can connect the EGM to external electronic 45 devices via wired or wireless communication.

FIG. 3 is a block diagram illustrating a method 100 according to embodiments described herein. According to such method 100, an absence of activity at a plurality of EGMS can be registered 102 over a predetermined period of time and an electronic control signal can be transmitted 104 to lighting devices associated with the inactive EGMS. The signal can control 106 the lighting devices to commence a synchronized attract mode where the lighting elements or indicators are illuminated with more intensity or flash at a more rapid pace. As described previously, such attract mode can be generated across lighting devices associated with a plurality of inactive EGMS and can include distinctive patterns and/or progressions which can draw attention to the inactive EGMS.

55 At any time, activity can be detected 108 at one or more of the EGMS and a control signal can be electronically transmitted 110 to the lighting devices to adjust the lighting effect. For example, the lighting devices can be adjusted 112 60 to produce a coordinated or synchronized emotive style lighting effect where lighting devices at or proximate an active EGM are dimmed, deactivated or slowed. As

described previously, the detected activity can be any the initiation of a game or game program, the deposit of a wager, movement at or around an EGM or any additional event or condition capable of being performed, input or detected by the EGM.

As will be understood by those of ordinary skill in the art, while the description above details the preferred and best mode(s) of practicing the invention, many other configurations and variations are possible. For example, the invention need not be practiced with a commercial/regulated gaming system, but could be used with a variety of coin-operated amusement devices, home gaming systems, or any other appropriate system. Accordingly, the scope of the invention should be determined not by the embodiment(s) illustrated, but by the claims below and their equivalents.

From the foregoing, it will be observed that numerous variations and modifications may be effected without departing from the spirit and scope of the invention. It is to be understood that no limitation with respect to the specific apparatus illustrated herein is intended or should be inferred. It is, of course, intended to cover by the appended claims all such modifications as fall within the scope of the claims.

Further, logic flows depicted in the figures do not require the particular order shown, or sequential order, to achieve desirable results. Other steps may be provided, or steps may be eliminated, from the described flows, and other components may be added to, or removed from the described embodiments.

What is claimed is:

1. A system for providing lighting effects for a plurality of electronic gaming machines comprising:

a plurality of lighting devices operatively connected to the plurality of electronic gaming machines, each of the plurality of lighting devices having at least one lighting element for providing illumination, the plurality of lighting devices comprising a first lighting device at a first gaming machine of the plurality of gaming machines;

the plurality of lighting devices configured to produce the lighting effects for the plurality of gaming machines, the lighting effects comprising synchronized lighting effects across the plurality of lighting devices at the plurality of gaming machines and individual lighting effects on the first lighting device at the first gaming machine;

the synchronized lighting effects comprising a coordinated attract mode and an emotive lighting mode, at least some of the plurality of lighting devices being synchronized during the coordinated attract mode to present a visual effect where illumination provided by a lighting element is presented as virtually traveling across the plurality of gaming machines;

the individual lighting effects comprising an active lighting mode separate from the coordinated attract mode, wherein the first lighting device is synchronized in the coordinated attract mode and a condition triggered on the first electronic gaming machine removes the first lighting device from the coordinated attract mode and initiates the active lighting mode on the first lighting device,

wherein in response to the condition triggered on the first electronic gaming machine, the emotive lighting mode is initiated on a second lighting device of the plurality of the lighting devices, the second lighting device being at a second gaming machine of the plurality of gaming machines, the second gaming machine being proximate the first gaming machine, and

wherein the emotive lighting mode has reduced lighting effects from the lighting effects of the coordinated attract mode, the reduced lighting effects comprising at least one of reduced brightness or slower frequency of illumination from the lighting effects of the coordinated attract mode.

2. The system of claim 1 where the active lighting mode comprises reduced lighting effects from the lighting effects of the coordinated attract mode, the reduced lighting effects of the active mode comprising at least one of reduced brightness or slower frequency of illumination from the lighting effects of the coordinated attract mode.

3. The system of claim 1 where the active lighting mode comprises lighting effects being produced by the first lighting device that are coordinated with graphics electronically displayed on an electronic display screen of the first electronic gaming machine.

4. The system of claim 1 where the plurality of lighting devices are operatively connected to a programmable control device having associated control circuitry, the first lighting device being controlled by the control device to remove the first lighting device from the coordinated attract mode to implement the active lighting mode.

5. The system of claim 1 where each lighting device of the plurality of lighting devices is electronically coupled to one of the plurality of gaming machines, each lighting device of the plurality of lighting devices being controlled by a programmable control device of the gaming machine to which it is connected.

6. The system of claim 1 where the lighting effects further comprise individual lighting effects on the second lighting device at the second gaming machine, and where the second lighting device is synchronized in at least one of the coordinated attract mode or the emotive lighting mode, a condition triggered on the second electronic gaming machine removes the second lighting device from at least one of the coordinated attract mode or the emotive lighting mode and initiates the active lighting mode.

7. The system of claim 1 further comprising at least one of the plurality of electronic gaming machines.

8. The system of claim 1 where the condition comprises an occurrence of a predetermined event registered during a game played on the first gaming machine.

9. The system of claim 1 where the plurality of lighting devices are housed within cabinets of the plurality of gaming machines.

10. The system of claim 1 where the coordinated attract mode is implemented where the systems registers an absence of credits input into the plurality of gaming machines for a predetermined period of time.

11. The system of claim 1 where the coordinated attract mode includes at least one of a more rapid sequence of illumination or an increase in brightness of the lighting elements over a default lighting condition.

12. The system of claim 1 where the lighting element comprises at least one of a light emitting diode, incandescent lamp, cold cathode, laser or fluorescent, halogen or neon lamp or tube.

13. A method comprising:
electrically transmitting a first signal to a plurality of lighting devices operatively connected to a plurality of electronic gaming machines, the first signal controlling the plurality of lighting devices to initiate a synchronized attract lighting mode across the plurality of electronic gaming machines, at least some of the plu-

rality of lighting devices being coordinated during the synchronized attract lighting mode to present a visual effect where illumination provided by a lighting element is presented as virtually traveling across the plurality of gaming machines;

initiating the synchronized attract lighting mode at the plurality of lighting devices;

registering an occurrence of a predetermined event during a game played on a first gaming machine of the plurality of gaming machines;

electrically transmitting a second signal to a first lighting device of the plurality of lighting devices, the first lighting device being electrically coupled to the first gaming machine, the second signal instructing the first lighting device to terminate the synchronized attract lighting mode and initiate an active lighting mode, the active lighting mode producing an individual lighting effect different from the visual effect of the synchronized attract lighting mode;

terminating the synchronized attract lighting mode on the first lighting device; and

initiating the active lighting mode on the first lighting device;

electronically transmitting a third signal to a second lighting device of the plurality of lighting devices, the second lighting device being at a second gaming machine of the plurality of gaming machines, the second gaming machine being proximate the first gaming machine, the third signal instructing the second lighting device to terminate the synchronized attract lighting mode and initiate an emotive lighting mode; and

initiating the emotive lighting mode on the second lighting device, the emotive lighting mode having reduced lighting effects from the lighting effects of the coordinated attract mode, the reduced lighting effects comprising at least one of reduced brightness or slower frequency of illumination from the lighting effects of the coordinated attract mode.

14. The method of claim 13 where the active lighting mode comprises reduced lighting effects from the visual effect of the synchronized attract lighting mode, the reduced lighting effects of the active mode comprising at least one of reduced brightness or slower frequency of illumination from the visual effect of the synchronized attract mode.

15. The method of claim 13 where the active lighting mode comprises lighting effects being produced by the first lighting device that are coordinated with graphics electronically displayed on an electronic display screen of the first electronic gaming machine.

16. The method of claim 13 further comprising:
registering an occurrence of a predetermined event during
a game played on the second gaming machine;
electrically transmitting a fourth signal to the second
lighting device;
the fourth signal instructing the second lighting device to
terminate at least one of the synchronized attract lighting
mode or the emotive lighting mode and initiate the
active lighting mode, and
terminating at least one of the synchronized attract lighting
mode or the emotive lighting mode on the second
lighting device, and
initiating the active lighting mode on the second lighting
device.

17. The method of claim 13 further comprising, terminating
the active lighting mode on the first lighting device and
returning the first lighting device to the synchronized
attract lighting mode.

18. The system of claim 1 further comprising a third
lighting device of the plurality of lighting devices, the third
lighting device remaining in the coordinated attract mode
when the first lighting device is in the active lighting mode
and the second lighting device is in the emotive lighting
mode.

19. The method of claim 17 further comprising terminating
the emotive lighting mode on the second lighting device and
returning the second lighting device to the synchronized
attract lighting mode.
